ROCKET FUSE

Harry G. Jones, Jr., Arlington County, Va., and Casper J. Kooper and Francis P. Gilhooly, Huntsville, Ala., assignors to the United States of America as represented by the Secretary of the Army

Application October 9, 1951, Serial No. 250,556

2 Claims. (Cl. 102—78)

(Granted under Title 35, U. S. Code (1952), sec. 266)

The invention described in the specification and claims may be manufactured and used by or for the Government for governmental purposes without the payment of any royalty thereon.

This invention relates in general to actuating devices and more particularly has reference to a fuse construction for use with a projectile.

In fuses of the type used with rockets it is customary to provide a safety bolt which is ejected during flight to release an element of the firing mechanism for movement to armed position.

In the present invention the bore riding pin accomplishes the same purpose as in the fuses of the prior art but the pin is additionally associated with a safety set back sleeve to hold it in locked position when a fuse clamp or band is in place, as well as when the band or clamp is removed to insure complete safety during handling.

It is accordingly an object of our invention to produce a simple and effective combination fuse which will allow a projectile to be handled with safety and yet insure certain arming of the fuse when the projectile is launched.

Another object is to provide a fuse which is unaffected by shocks or movement and which is positively locked against inadvertent operation prior to use, and the functioning of which is insured on passing from the launching mechanism.

In order to make our invention more clearly understood we have shown in the accompanying drawings means for carrying the same into practical effect in which:

Figure 1 is a longitudinal section of the fuse forming the subject matter of this invention showing the relation of the parts of the fuse prior to the launching of the carrying rocket.

Figure 2 is a cross section taken on lines 2—2 of Figure 1 looking in the direction of the arrows.

Figure 3 is a fragmentary view taken on lines 3—3 of Figure 2 looking in the direction of the arrows.

Referring more particularly by numerals to the drawings in which same and similar elements are designated by like symbols of reference throughout and more especially to Figure 1 there is shown the structure forming the subject matter of this invention comprising a rocket casing 1 including the usual explosive charge 2 and a booster charge 3 contained within cup 4 threadedly fitted into annulus 6 which embraces a primer 8 and is threadedly fitted into casing 1 as shown. Annulus 6 has therein a bore 10 of smaller diameter than the diameter of the primer receiving passage, opening into firing pin cavity 11 and is aligned with and receives the sharp end of firing pin 14 as will later appear. Slidably fitting into the casing is bore riding pin 12 which has a cap 15 riveted or otherwise secured thereto and a helical spring 18 surrounding and pressing it outwardly of the casing. Bore riding pin 12 has a longitudinal recess cut therein and communicating with the surface thereof by a narrow passage thereby forming fingers 21 and 22 for a purpose to be presently explained. The bore riding pin 12 is cut

2

away adjacent finger 22 to form an arcuate section 24 which in normal unarmed position extends between firing pin 14 and bore 10. The pin 12 is further cut away beyond the arcuate section 24 to form a flat tip 26 and abuts sleeve 30 as shown in Figure 2. Plunger 35 comprising the frustum of a right cone is disposed within firing pin cavity 11 and has an integral turned out flange 39 in contact with turned out flange 38 of liner sleeve 30. Helical spring 37 seats between sliding safety set back sleeve 36 and flange 38 and resiliently urges them apart. Sliding safety sleeve 36 has a bore 40 therethrough to receive nose 42 of spring based detent button 43 and an elongated bore 44 in part aligned with elongated bore 51 to receive the nose 45 of locking stud 46, which is threadedly engaged in a drilled passage in the casing and which prevents rotation of the sleeves about the axis of the casing but does not prevent their longitudinal movement. A vent 48 leads through the casing and through aligned ports in sleeves 36 and 30 to prevent any possible pressure build up in cavity 11. Aligned passages 49 and 50 are provided to receive fingers 21 or 22 depending upon the position of the bore riding pin.

The "all ways" firing pin is here used to insure positive operation of the fuse under all conditions of target contact. If the projectile strikes a target on the ogival a force is applied to plunger 35 inclined to its axis of symmetry. However since the plunger is the frustum of a cone the component of the force in the direction of free motion of the plunger is effective to accelerate the same to cause motion in the direction of the firing pin.

The firing pin assembly comprises a substantially triangular flat plate 52 having its apex cut away and integral feet 53 at the base thereof. Pin 14 is riveted or otherwise secured to one side of the plate and the rivet further secures spring 54 thereto. Spring 54 bends back upon itself and is additionally bent at a right angle to pierce the plate 52 as is best shown in Figures 2 and 3. The lower edge of plate feet 53 rest in annular groove 23 and cut away portions of sleeve 30 rest against the upper edges of the feet whereby plate 52 forms a lever of the third order with the fulcrum located at the lower edge of the feet, the force to be applied by sleeve 30 at the upper edge of the feet and the load 14 arranged to follow an arcuate path. Spring 54 bears against annulus 6 whereby the firing pin assembly normally maintains a position inclined to the axis of the fuse.

Operation

During storage and shipping a safety band (not shown) is clamped around the body of the fuse and forces bore riding pin 12 inwardly whereby finger 21 pierces sleeve bore 49 to hold the sleeve 36 in place. When the projectile is to be fired the band is removed and the spring 18 thereupon urges pin 12 outwardly until opposed finger 22 pierces sleeve bore 49 and thereby locks the pin in place while the artilleryman is loading the tube. It can be readily seen that when the projectile is within the tube the pin cap 15 bears thereagainst and holds the fingers 21 and 22 spaced from sleeve 36. When the projectile is fired in the usual well known way the force of set back rams the sleeve 36 rearward against the urging of spring 37 and bore 40 passes under detent 43 whereupon detent spring 47 forces nose 42 into bore 40 and locks the sleeve to clear the path of travel for bore riding pin 12 which is ejected from the fuse when the projectile passes beyond the tube, thereby removing the arcuate portion 24 of pin 12 from its position between pin 14 and primer 8.

When the projectile strikes a target the plunger moves violently forward carrying with it sleeve 30 against the urging of spring 37. It will be noted that the plunger does not engage the firing pin spring 54 and that its motion is relatively short. When sleeve 30 moves it im-

parts a turning couple to plate 52 which pivots as a lever about its fulcrum, the base of feet 53 and against the resilience of spring 54; and pin 14 moves through an arc into bore 10 to explode the primer 3 which in turn ignites the booster 3 and fires charge 2.

From the foregoing taken in connection with the accompanying drawings it will be seen that novel provision has been made for effecting the desired improvements and while preferred details have been shown variations may of course be made within the scope of the invention as claimed.

We claim:

1. In a fuse having a body and suitable for use with fin stabilized projectiles adapted for launching from a tube, a primer fixed in said body, a triangular plate disposed at an angle to said primer, spring means biasing said plate in a first direction about the base thereof as a fulcrum, a firing pin affixed at one end of said plate, a first sleeve coaxial with said primer and engaging the said plate, a plunger within and movable with said first sleeve, a second sleeve embracing the said first sleeve, a safety member adapted to engage said tube and having opposed fingers arranged in facing relation, said fingers adapted to enter an opening in said second sleeve, and a spring urging the said safety member outwardly of the said body to eject the same in flight, whereby upon engagement of the said body with a target the said plunger travels forward forcing the said first sleeve to move the said plate in a second direction about the base thereof to deliver the said firing pin into engagement with the said primer.

2. In a fuze having a body, and suitable for use with rockets adapted for launching from a tube, an annulus axially secured therein, an instantaneous fire primer disposed within an axial bore in said annulus said body being provided with an annular groove adjacent one end of said annulus, means for firing said primer comprising a substantially triangular plate having its apex area

cut away and defining a pair of integral feet at its base area, said feet normally riding in said annular groove in said body, a firing pin, a flat spring member connected at one end to said plate by said firing pin, said spring being bent backwards upon itself and additionally bent at a right angle to pierce said plate and bear at its other end against said annulus, a first sleeve slidable in said body having a cut away portion at its forward end and adapted to receive and bear against the upper edges of said feet on said plate, a plunger movable with said first sleeve upon target impact to rotate said plate about its feet as a pivot, a second sleeve slidable with respect to said first sleeve, a coil spring urging apart the respective ends of said first and second sleeves, a detent operable to engage said second sleeve and lock the same during set back, a bore riding pin slidably mounted within a transverse bore in said body of said fuze, said bore riding pin defining a flat tip portion, said tip having a longitudinal groove receiving the end of said firing pin, said bore riding pin normally separating said firing pin from said primer when fuze is in unarmed position, said bore riding pin further defining, along its intermediate portion, a longitudinal recess and a pair of opposed fingers spaced on either side of said recess and adapted to engage an opening in said second sleeve intermittently upon reciprocal movement of said bore riding pin and prevent axial movement of said second sleeve.
